UNITED STATES PATENT OFFICE.

WILLIAM R. NOÉ, OF NEWARK, NEW JERSEY, ASSIGNOR TO HOLMES, BOOTH & HAYDENS, OF WATERBURY, CONNECTICUT.

DESIGN FOR A PENDANT FOR LAMPS, &c.

SPECIFICATION forming part of Design No. 16,355, dated October 27, 1885.

Application filed September 16, 1885. Serial No. 177,311. Term of patent 7 years.

To all whom it may concern:

Be it known that I, WILLIAM R. NOÉ, a citizen of the United States, residing at Newark, in the county of Essex and State of New Jersey, have invented a certain new and original Design for Pendants for Lamps, &c.; and I do hereby declare the following to be a full, clear, and exact description of the invention, such as will enable others skilled in the art to 10 which it appertains to make and use the same.

Figure 1 is a side elevation of a lamp-shade support or ring ornamented in accordance with my design. Fig. 2 is an enlarged detail view of the ornamental pendant detached from the 15 shade supporter or ring.

The leading feature of my design is the ornamental pendant, which consists, essentially, of the bell *e*, adapted to be attached to the shade supporter or ring. I may, however, use in 20 connection with the bell a rosette, *a*, the two being loosely connected together by means of a suitable link-hook or other connecting device, *b*.

Several of the above-described pendants 25 are attached at intervals upon a shade-ring, *A*,

as shown. They may be attached at any portion of the ring or supporter; but they are preferably attached to a flange thereon. The bell may be either a real one or a representation of one, and it may have its exterior engraved with suitable design or made with other ornamentation, either in relief or intaglio, as desired. The rosette also may be of any suitable ornamental outline or configuration. 30

What I claim is—

1. The design for a pendant, consisting of the rosette *a* and a bell or representation thereof, as set forth. 35
2. The design for a lamp-shade supporter or ring, substantially as herein shown and described, the same consisting of a supporting-ring having bells or representations thereof attached thereto, as set forth. 40

In testimony whereof I affix my signature in presence of two witnesses.

WILLIAM R. NOÉ.
